UNITED STATES PATENT OFFICE

2,459,041

AUTOMATIC TIMING DEVICE

William H. Mitsch, Wheeling, W. Va.

Application February 9, 1946, Serial No. 646,674

2 Claims. (Cl. 171—97)

1

This invention appertains to automatic timing devices generally, and more particularly to one which, while being capable of use as a sequence timer for any machine or process, is especially adapted to the operational control of resistance welding machines employing air pressure for applying the electrodes to the work.

At present, sequence timers are manufactured in a variety of forms, most of which depend for their operation upon the charge and discharge of capacitors in electronic tube circuits and wherein a condenser is charged through a resistor and, at a predetermined voltage, the electronic tube conducts enough current to operate a relay. Hence, by interconnecting a number of such circuits, a sequence of operations is controlled. Another form of sequence timer, to produce a variable time delay, employs filtered air which is forced through a graduated adjustable orifice, so that, by employing a number of such units, a sequence of operations can be controlled. Motor driven sequence timers are also well known but operate with the disadvantage that one time period cannot be changed without altering the speed, or changing the other time periods.

However, in the instant invention, it is an object to make use of the magnetic flux of an expanding or collapsible field to obtain the desired time period and, to such end, four time-delay relays, operating on this principle, are employed to control a resistance welding machine of the spot or projection type, in the operation of which, four periods of time are required, the same being commonly known as "squeeze," "weld," "hold," and "off."

Another object of the invention has to do with providing each of the aforesaid time-delay relays with a means of adjustment, so that, the time periods in the operation thereof can be readily and easily varied with precision to meet any of a wide range of work requirements.

With the foregoing and other objects and advantages of equal importance in view, the invention resides in the certain new and useful combination, construction, and arrangement of parts and circuits, as will be hereinafter more fully described, set forth in the appended claims, and illustrated in the accompanying drawings, in which:

Figure 1 is a side elevational view, partly in section, of a panel mounting for certain of the operational elements of the timing device, and showing diagrammatically the circuit connections between certain of the operational elements

2

and the operating parts of a welding machine, in accordance with the invention;

Figure 2 is a somewhat enlarged, fragmentary, section, taken on the line 2—2 of Figure 1, looking in the direction of the arrows;

Figure 3 is a diagrammatical view of the control circuits of the device; and,

Figure 4 is a diagrammatical view, showing the order of operation of the several relays for controlling the welding machine through two complete cycles of its operation.

Referring to the drawings, and more particularly to Figures 1 and 2, the control panel, as it is exemplified therein, is comprised in a mounting panel 10, having an angled bracket 12, fastened horizontally on its rear side, to support four time-delay relays 16, 18, 20, and 22, in vertical position and in line thereon; two of the relays at each side of a rectifier tube 14, also supported on the bracket. The lower or heel end of the frame 24, of each of the relays, is fastened, by means of a screw 26 (Figure 2), to the horizontal portion of the bracket 12, while the heel end of the core 28 is fastened, by means of a screw 30, to the like end of the frame; the horizontal portion of the bracket being apertured, as at 32, to permit of access to the screw 30, without need to dismount the relay from the bracket.

In order to adjust the time period of operation of each of the relays 16, 18, 20, and 22, a collar 34, of copper or an alloy thereof, is slidably mounted on the core 28, between the heel ends of the frame 24 and the relay coil, and it is formed with an arm 36 extending in spaced parallel relation to the core and downwardly through an opening 40, formed in the bracket 12. One side of the arm 36 is formed with a series of rack teeth 38, arranged in mesh with a gear 42, which is keyed on the inner end of a shaft 44, that has bearing in the secured portion of the bracket 12 and the mounting panel 10; the opposite end of the shaft 44, at the front side of the panel, being provided with a control knob 46. Mounted on the shaft 44, between the panel 10 and the knob 46, is an index 48, having the form of a pointer which is turnable with the shaft and relatively to a graduated scale (not shown), delineated on the panel face. A guide

50 roller 50 is mounted on a stud 52, fixed in the secured portion of the bracket 12, and has rotating contact with the arm 36, at a point thereon directly opposite to that of the gear 42, in order to accurately guide the arm in its linear movements of adjustment, when the shaft 44 is turned

by a manipulation of the knob 46. The relay 16 is provided with cooperating contact sets 16a, 16b, and 16c; the relay 18, a contact set 18a; the relay 20, contact sets 20a and 20b; and the relay 22, contact sets 22a and 22b.

Also mounted on the panel 10, is a control transformer 54, which is centered thereon between a pair of relays 56 and 58; the relay 56 to control the operation of the compressed air valve that, in turn, controls the operation of the movable electrode of the welding machine, and the relay 58, the operation of the contactor during the weld period of the latter. A control switch 60, preferably of the push button type, is carried at the free ends of a pair of leads extending from a set of circuit terminals 62 on the panel 10, while A.-C. power line leads are connected to a set of terminals 64, also on the panel, in circuit with a section S' of the secondary winding S, of the transformer 54. The relay 56 is provided with a pair of fixed contacts and a movable bridging contact 56a, with the fixed contacts connected to a pair of terminal posts 66, while the relay 58 is likewise provided with a pair of fixed contacts and a movable bridging contact 58a, with its fixed contacts connected to a pair of terminal posts 68. One of the terminal posts 66 is connected to one side of the solenoidal valve coil 80 and the other terminal post to one side of the A.-C. power line and one of the terminal posts 68, of the relay 58, while the second of the latter is connected to one side of the solenoidal contactor coil 86, which has its other side, along with the other side of the solenoidal valve coil 80, connected to the remaining side of the power line.

The welding machine, as illustrated in Figure 1, is a conventional type, and includes a frame 70, supporting a cylinder 72, housing a piston 74, which is connected to a movable electrode 82. The cylinder 72 is provided with an inlet 76 for connection to a suitable source of fluid pressure (not shown), such as compressed air, for the actuation of the piston 74; a valve element 78 being mounted in the frame 70 and adapted to be actuated by a solenoidal coil 80. A fixed electrode 84 is supported by, but insulated from, the lower part of the frame 70, for cooperation with the movable electrode 82. Leads 90, from the electrodes 82 and 84, are connected to the secondary winding of the welding transformer T, the primary winding of which is connected to the power line, with one of its leads severed for connection with the fixed contacts of the welding circuit contactor, which contacts are adapted to be bridged by a movable contact member 88, upon the energization of the solenoidal coil 86 that occurs whenever the relay 58 is operated.

In the circuit arrangement shown in Figure 3, the contacts 16a, 18a, and 20a, of the relays 16, 18, and 20, respectively, are normally closed, while all of the others thereof and of the remaining relays 22, 56, and 58, are open. With the A.-C. power line leads connected to the terminal posts 64, the supply voltage is applied to the primary winding P, of the transformer 54, and the filament cathode of the vacuum tube 14 heats up; the energizing current for the filament cathode being furnished by the section S', of the secondary winding S of the transformer 54, and the direct current for the electromagnetic windings of the several relays 16 through 22, by the rectification of the A.-C. generated in the other section. After the elapse of a few seconds, the tube 14 furnishes a direct current which immediately

acts to energize the coils of the relays 18 and 22, causing the contacts 22a and 22b to close and the contacts 18a to open. By now closing the push button switch 60, the coil of the relay 16 is energized, causing the contacts 16b and 16c to close and the contacts 16a to open; the contacts 16b, when closed, forming a holding circuit for the coil of the relay 16, and the contacts 16c, causing the energization of the coil of the power control relay 58 and the closing of the contacts 58a, of the latter, on the solenoidal coil 80 for the operation of the compressed air valve 78 of the welding machine. With the closing of the contacts 16b and 16c, as aforesaid, the push button switch 60 may be released to its normally open circuited position. With the opening of the contacts 16a, of the relay 16, the coil of the relay 18 is de-energized and, after a delay, the contacts 18a thereof closes; the delay, as before stated, being due to the time-delay, or slow release, characteristics of the several relays 16, 18, 20, and 22. This delay interval constitutes the "squeeze" period of the movable electrode 82 relatively to the fixed electrode 84 and the work interposed therebetween. With this closing of the contacts 18a, of the relay 18, the coil of the relay 20 is energized, causing the contacts 20b to close on the coil of the power control relay 58, which acts to close its contacts 58a on the solenoidal coil 86, of the contactor of the welding machine. With the activating of the solenoidal coil 86, the contacts 88 close on the welding transformer, for the application of the secondary current of the latter to the electrodes 82 and 84. At this time, the contacts 20a, of the relay 20, open to effect a de-energizing of the coil of the relay 22, and, after an interval of time, its contacts 22a and 22b open; the time delay interval here constituting the "weld" period of operation of the welding machine. At the end of this delay period, the opening of the contacts 22b de-energizes the coil of the relay 58, causing the contacts 58a to open on the solenoidal coil 86 and the contacts 88 on the welding transformer and the electrodes 82 and 84. At the same time, the contacts 22a, of the relay 22, open and cause the de-energization of the coil of the relay 16. After a succeeding elapse in time, constituting the "hold" period of operation of the welding machine, the contacts 16a close and the contacts 16b and 16c open; the contacts 16a closing the circuit on the coil of the relay 18, while the contacts 16b breaks the circuit around the push button switch 60 and the contacts 16c cause the de-energization of the coil of the relay 56, along with the solenoidal coil 80, with the result of the return of the compressed air valve 78 to its normal position and the consequent separation of the movable electrode 82 from the work. With the latter closing of the contacts 18a, of the relay 18, the coil of the relay 18 is energized, causing the contacts 18a to open on the coil of the relay 20, the de-energizing of which, after a delay in time constituting the "off" period in the welding operation, causes its contacts 20a to close, thus restoring the timing system to its original state, ready for a repeat operation.

By reference to Figure 4, the sequential periods of inter-operation of the several relays 16, 18, 20, 22, 56, and 58, is to be readily visualized through two cycles of welding machine operation, each cycle being performed in accordance with the above description. However, if the push button switch 60 is opened at the time indicated, all further action of the timer will cease upon the

completion of a single cycle of welding machine operation, but, if the switch 60 is held closed, the sequential operation of the relays will be repeated for any given number of cycles thereof. Again, if the switch 60 is opened at any time, after its initial closing to initiate the operation of the timing system, the operational sequence of the relays will continue to complete the welding cycle as before stated.

While in the foregoing I have described my invention in connection with an exemplary use thereof, it is to be understood that my timing system may be employed with any type of machine or process involving sequential operative steps other than as herein disclosed. Hence, while I have described my invention in its preferred embodiment, it is also to be understood that the words which I have used are words of description rather than of limitation, and that changes within the purview of the appended claims may be made without departing from the true scope and spirit of my invention in its broader aspects.

What I claim is:

1. An electric sequence timer system, comprising a D. C. control circuit, an A. C. power circuit, a transformer including a primary winding connected in said power circuit and a secondary winding in said control circuit, a rectifier connected to and between said secondary winding and said control circuit to supply D. C. to the latter, a plurality of electromagnetic relays connected in said control circuit, a plurality of electromagnetic switches connected in said power circuit, and a manually operated switch connected in said control circuit, one of said relays having its winding connected in series with said switch and a pair of normally open contacts in series with said winding and shunted about said switch, a second of said relays having its winding connected in said control circuit and in parallel with the winding and contacts of said one relay and in series with a second pair of normally closed contacts of the latter, said second relay having a pair of normally closed contacts connected in said control circuit and in parallel with its winding, a third of said relays having its winding connected in said control circuit and in parallel with the winding of said second relay and in series with the contacts of the latter, said third relay having a pair of normally closed contacts connected in said control circuit and in parallel with its winding, a fourth of said relays having its winding connected in said control circuit and in parallel with the winding of said third relay and in series with the contacts of the latter, said fourth relay having a third pair of normally open contacts connected in said control circuit and in series with the winding of said one relay, said one relay having a third pair of normally open contacts

connected in said power circuit and in parallel with the primary winding of said transformer, one of said electromagnetic switches having its winding connected in said power circuit in series with said third pair of contacts and having a pair of normally open contacts also connected in said power circuit and in parallel with its winding and in series with the winding of an electromagnetic device for the operative control thereof, said third relay having a second pair of normally open contacts connected in said power circuit and in parallel with the winding of said one electromagnetic switch and in series with a second pair of normally open contacts of said fourth relay and the winding of a second of said electromagnetic switches, said second electromagnetic switch having a pair of normally open contacts connected in said power circuit and in parallel with its winding and in series with the winding of a third electromagnetic switch, said one electromagnetic switch having a pair of normally open contacts connected in said power circuit and in parallel with its winding, said third electromagnetic switch having a pair of normally open contacts connected in said power circuit and in parallel with its winding and in series with the primary winding of an output transformer, whereby, upon the momentary closing of said manually operated switch, the windings of said relays and said electromagnetic switches will be sequentially energized to perform their respective functions through a single cycle of operation.

2. The invention as defined in claim 1, with each of said electromagnetic relays of a delayed action type and provided with means for the adjustment of the time delay period of operation thereof.

WILLIAM H. MITSCH.
